PUMP JACK VALVE CONTROL MECHANISM

Samuel V. Smith, Long Beach, Calif.

Application April 23, 1949, Serial No. 89,251

5 Claims. (Cl. 121—164)

1

This invention has to do generally with fluid pressure operated pump jack mechanisms particularly of the type dealt with in my copending application Serial Number 14,355, filed March 11, 1948 on Well Pumping Equipment, now Patent No. 2,564,285, issued August 14, 1951, and has for its general object to provide improved mechanisms for actuating a pressure fluid control valve in accordance with the travel of the jack piston.

The pump jack proper may be characterized as comprising a vertically positioned cylinder, or cylinder assembly, containing a single or multiple piston assembly reciprocable vertically by the applied fluid pressure to operate the work, such as a well pump. The invention contemplates operation of the actuating fluid control valve by a mechanism employing a cam carried directly by an upper portion of the piston contained within a vertically extended housing, and operable to actuate a housing supported mechanism, the movements of which are transmitted to the control valve.

In accordance with its preferred embodiment, the invention employs a pair of vertically spaced movable elements extending from the outside of the housing into the interior thereof for direct engageability by the piston-carried cam means. While it is broadly contemplated that various types of mechanisms may be employed for transmitting movement of said element to the control valve, it is preferred to connect the elements for simultaneous movement, and specifically by way of flexible connections such as cables, the advantages of which will later develop.

The invention has various specific objects and novel details, all of which will appear from the following description of a typical and illustrative embodiment of the invention shown by the accompanying drawing, in which:

Fig. 1 is a general view illustrating the pump jack proper and pressure fluid supply system;

Fig. 2 is an enlarged fragmentary view showing the position of the valve actuating parts at the start of the piston up-stroke;

Fig. 3 is a similar view showing the positions of the parts at the start of the piston down-stroke; and

Fig. 4 is a fragmentary section on line 4—4 of Fig. 2.

Referring first to the general showing of Fig. 1, the pump jack unit generally indicated at 10 and adapted to be positioned above and in axial alignment with a well bore, is shown to comprise a cylinder assembly 11 containing a vertically reciprocable piston assembly 12 which carries

2

and operates the well pump rod 13. The cylinder assembly 11 comprises a base 14, an inner tubular section 15, an intermediate cylinder 16, and an outer cylindrical shell 17 on which is mounted the head 18 containing annular fluid passage 19. The piston assembly 12 comprises an outer section 20 carrying a head 21 contained within space 22 and having sliding, substantially fluid tight engagement with the surfaces of the cylinder sections 16 and 17. The piston section 20 is spaced from the cylindrical shell 17 at 23 to permit communication of fluid pressure from the cylinder head space 19 through the annular clearance at 24 to the piston face 25. As illustrated, the piston has sliding, fluid-tight engagement at 26 within the cylinder head 18. The piston assembly includes an inner section 28 carrying a head 29 reciprocable within space 30 and having substantially fluid-tight engagement with the cylinder sections 15 and 16. The pump rod 13 may be supported by the upper closed end 31 of the piston assembly, as by carrying the rod on a removable bearing or bushing 32.

As more fully described in my copending application referred to above, the piston assembly 12 is adapted to be operated by maintaining a constantly applied elevating pressure, specifically air pressure from receiver 33, while alternately applying fluid pressure, specifically that of oil from the reservoir 34, to reciprocate the piston assembly. More complete details concerning the pressure fluid supply system appear in the other application. For present purposes, the following description of the pressure fluid system will suffice.

The compressed air maintained in receiver 33 at the proper pressure level required for operation of the piston, is communicated through pipe 35 to the cylinder space 22 so that the air pressure constantly exerts an elevating force against the piston face 36. Oil from reservoir 34 is discharged by pump 37 through line 38 to a master valve 39 which operates to alternately meet the oil under pressure through lines 40 and 41 respectively to space 30 and the piston face 42, and spaces 19, 23 and the piston face 25. Return oil flow from the master valve 39 to the reservoir 34 occurs through line 43. As will be understood, the piston assembly is driven on its down stroke by the weight of rod 13, the pump parts carried thereby and the oil pressure against the piston face 25, all acting to overcome the resistance of the air pressure applied to the piston face 36, at least throughout the latter portion of the piston down-stroke. The piston assembly and its rod

are elevated by air pressure against face 36 and the oil pressure acting against the piston face 42.

The operation of master valve 39 is controlled by oil pressure communicated from line 38 through pipe 44 and lines 45 and 46, under control of a suitable pilot valve 47 which in turn is reciprocally operated by rod 48. Oil is returned from the pilot valve to the reservoir 34 through line 49. Provision may be made for controlling the hydraulic pressure at the discharge side of the pump 37 in accordance with the air pressure in receiver 33, as through the by-pass of oil from line 38 through pipe 50 into line 43, under control of a suitable regulator valve assembly 51 which in turn is controlled by air pressure communicated from the receiver through line 52.

The present invention is more particularly concerned with an improved control mechanism generally indicated at 53, for actuating the pilot valve 47 by reciprocation of its rod 48 in accordance with the travel of the piston assembly 12. Referring particularly to Figs. 2 and 3, the upper end of the piston is shown to carry an annular cam 54 having angular faces 55 and 56, which reciprocates vertically within a cylindrical housing 57 carried by and extending above the cylinder head 18. Mounted on the housing 57 are vertically spaced pairs of arms 58 and 59, each arm containing an outer end slot 60 within which is supported a pivot 61 adjustable longitudinally of the supporting arm. The cylinder head 18 may carry a third pair of arms 62 which supports the adjustable pivot 63. Arms 58 and 59 support respectively the levers 64 and 65 mounted for swinging movement about the pivot 61. Arms 62 carry a link 66 which swings about pivot 63 and has an arm 67 pivotally connected at 68 with the valve actuating rod 48. Levers 64, 65 and the link 66 are connected for swinging movement together, preferably by flexible members or cables 69 and 70 having couplings 71 which are pivotally attached at 72 to the levers.

Lever 64 carries at its inner end a bifurcated extension 74 extending through slot 75 in the housing 57 and pivoted at 76 to the lever proper. Swinging movement of the extension 74 in one direction relative to the body of the lever is resisted by coil spring 77 terminally connected to the lever-carried arm 81 and the extension-carried arm 771. Movement of the lever extension 74 is limited in the Fig. 2 position by engagement of the stop 78 with the top edge of the lever 64. The extension 74 carries a roller 79 engageable by the cam 54 to actuate the lever and connected parts, as in a manner later explained.

Lever 65 similarly carries a bifurcated extension 80 pivoted on the lever-carried pin 81 and swingable downwardly by gravity from the solid line position established by the engagement of stop 83 with the bottom edge of the lever, to the broken line position 84. Extension 80 projects through the housing slot 85 and carries the roller 86.

The described lever and cable system may be balanced in any suitable manner so that the mass or weight at the right hand side of the pivots 61 and 63 will balance the weight or mass at the left hand side where the described roller assemblies are carried. Typically, cable 69 may carry a weight 88 of sufficient mass to maintain the system in balanced condition, and thereby assure effective and unimpeded operation of the control valve. Since the valve itself is mounted

for horizontal movement in the illustrated arrangement, and is thus not affected by gravity, the described counterbalancing of the cable and lever system or valve actuating mechanism also serves to balance the entire valve assembly that is, the actuating mechanism and the valve itself considered together as an operating unit.

In considering the operation of the valve control mechanism, assume the parts first to take the positions illustrated in Figs. 1 and 2, in which the piston assembly 12 is starting its up-stroke and the pilot and master valves 47 and 39 are positioned to deliver the pressurized hydraulic fluid through line 40 to the cylinder space 30. Having previously been displaced to the solid line position of Fig. 2, roller 86 will be passed by the cam 54. The latter then continues its up-stroke to the point of engaging the cam surface 56 against roller 79, whereupon lever 64 is swung clockwise about the pivot 61 to shift cables 69 and 70 respectively downwardly and upwardly, and rotate link 66 clockwise to throw the valve rod 48 to the left. Thereupon the pilot and master valve positions are reversed to cause the delivery of the pressurized hydraulic fluid through line 41 to cylinder space 23, thereby initiating the piston down-stroke. As the piston approaches the lower limit of its stroke, the cam face 55 engages roller 86 (which previously had become thrown from Fig. 2 position to that illustrated in Fig. 3 by the described cam actuation of lever 64) to again reverse the valve rod 48 through upward and downward displacement, respectively, of cables 69 and 70, and clockwise swinging of the levers 64, 65 and the link 66.

The roller-carrying lever extensions 74 and 80 are permitted swinging movement relative to the levers proper, in order to obviate the possibility of inadvertent actuation of the valve mechanism should for any reason either of the rollers in its intended radially outward position, project sufficiently in the path of the cam to otherwise cause the attached lever to be affected by the cam. For instance, should roller 79 after displacement to the intended Fig. 3 position, be returned sufficiently into the path of the cam as to be engageable by the face 55 as the piston starts down, the pivotal mounting of the extension 74 will permit its downward displacement relative to and without causing movement of the lever 64. Upon travel of the cam down past the roller, the latter is returned to its illustrated position by the spring 77. Similarly, should roller 86 remain (in the aspect of Fig. 2), within the path of the cam, upon engagement by the cam face 56, the roller and its carrier may be displaced to the dotted line position 84, without affecting the lever 65 and the connected valve control linkages.

I claim:

1. A fluid pressure operated jack mechanism comprising a vertically extending cylinder assembly, a piston assembly reciprocable vertically within said cylinder assembly, valve means for controlling the application of fluid pressure to said piston assembly, cam means carried by the upper portion of the piston assembly, a housing about the cam means and within which said cam means is vertically reciprocable, a pair of vertically spaced pivotally movable levers carried by said housing and actuatable selectively by said cam means during piston travel in opposite directions, each of said levers including an outer section and an inner section pivotally movable relative to the outer section upon engagement

by the cam means during its travel in one direction, a spring resisting said relative movement of the inner section of one lever, a valve actuating element pivotally mounted to the housing in substantial vertical alinement with said levers, a pair of flexible cables interconnecting said levers and said actuating element at the outer and inner sides respectively of their individual pivotal axes so that the levers and element move in unison, and means connecting said element to the valve means.

2. A fluid pressure operated jack mechanism comprising a vertically extending cylinder assembly, a piston assembly reciprocable vertically within said cylinder assembly, valve means for controlling the application of fluid pressure to said piston assembly, cam means carried by the upper portion of the piston assembly, a housing about the cam means and within which said cam means is vertically reciprocable, a pair of vertically spaced pivotally movable levers carried by said housing and actuatable selectively by said cam means during piston travel in opposite directions, each of said levers including an outer section and an inner section pivotally movable relative to the outer section upon engagement by the cam means during its travel in one direction, a spring resisting said relative movement of the inner section of one lever, a valve actuating element pivotally mounted to the housing in substantial vertical alinement with said levers, a pair of flexible cables interconnecting said levers and said actuating element at the outer and inner sides respectively of their individual pivotal axes so that the levers and element move in unison, means connecting said element to the valve means, and a counterweight carried by an outer one of said flexible cables for counterbalancing the weight of the inner ends of said levers.

3. A fluid pressure operated jack mechanism comprising a vertically extending cylinder assembly, a piston assembly reciprocable vertically within said cylinder assembly, valve means for controlling the application of fluid pressure to said piston assembly, cam means carried by the upper portion of the piston assembly, a housing about the cam means and within which said cam means is vertically reciprocable, a pair of vertically spaced pivotally movable levers carried by said housing and actuatable selectively by said cam means during piston travel in opposite directions, a pair of flexible cables interconnecting said levers at the two sides of their pivotal axes to interconnect them for simultaneous movement, and means for transmitting such movement to said valve means.

4. A fluid pressure operated jack mechanism

comprising a vertically extending cylinder assembly, a piston assembly reciprocable vertically within said cylinder assembly, valve means for controlling the application of fluid pressure to said piston assembly, cam means carried by the upper portion of the piston assembly, a housing about the cam means and within which said cam means is vertically reciprocable, a pair of vertically spaced pivotally movable levers carried by said housing and actuatable selectively by said cam means during piston travel in opposite directions, each of said levers including an outer section and an inner section movable relative to the outer section upon engagement by the cam means during its travel in one direction, means interconnecting said levers for simultaneous movement, and means for transmitting such movement to said valve means.

5. A fluid pressure operated jack mechanism comprising a vertically extending cylinder assembly, a piston assembly reciprocable vertically within said cylinder assembly, valve means for controlling the application of fluid pressure to said piston assembly, cam means carried by the upper portion of the piston assembly, a housing about the cam means and within which said cam means is vertically reciprocable, a pair of vertically spaced pivotally movable levers carried by said housing and actuatable selectively by said cam means during piston travel in opposite directions, each of said levers including an outer section and an inner section pivotally movable relative to the outer section upon engagement by the cam means during its travel in one direction, a spring resisting said relative movement of the inner section of one lever, means interconnecting said levers for simultaneous movement, and means for transmitting such movement to said valve means.
